MAURICE DEEKS, OF ROCHELLE PARK, NEW JERSEY.

CONCRETE-WALL MACHINE.

1,176,525.

Specification of Letters Patent. Patented Mar. 21, 1916.

Application filed July 10, 1915. Serial No. 39,087.

To all whom it may concern:

Be it known that I, MAURICE DEEKS, a subject of the King of Great Britain, and a resident of Rochelle Park, in the county of 5 Bergen and State of New Jersey, have invented a new and Improved Concrete-Wall Machine, of which the following is a full, clear, and exact description.

This invention relates to apparatus for 10 building plastic or concrete walls, and has particular reference to devices of this nature adapted for continuous operation for forming a wall in courses one above another in a rapid and reliable manner.

15 Among the objects of the invention is to simplify and improve the construction and method of operation of machines of this nature adapted for forming a hollow wall or a wall having inner and outer portions with 20 an air space between them.

A further object of the invention is to improve the facilities for making the wall not only self-supporting but so adapted as to support the building machine while the work 25 progresses.

A still further object is to improve the facilities for applying transverse braces or ties adapted to lock the two wall portions together, such braces or ties being positioned 30 by the machine employed in the wall construction.

With the foregoing and other objects in view, the invention consists in the arrangement and combination of parts hereinafter 35 described and claimed, and while the invention is not restricted to the exact details of construction disclosed herein, still for the purpose of illustrating a practical embodiment thereof reference is had to the accompanying drawings, in which like reference characters designate the same parts in the several views, and in which—

Figure 1 is a plan view illustrating a preferred embodiment of the invention; Fig. 2 is a side elevation of the same; Fig. 3 is an end elevation of the machine indicating its normal operative position in full lines and its loose transporting position in dotted lines, and showing a portion of the wall and supporting rails in cross section; Fig. 4 is a plan view indicating a means for forming a corner of a wall; and Fig. 5 is a perspective view of a corner core.

Referring now more particularly to the drawings, I show in the main views a ma-

chine comprising inner and outer parallel plates 10 and 11 paired respectively with outer plates 10' and 11' of preferably the same length and disposed in vertical planes. The inner plates 10 and 11 are adapted to 60 form the opposite inner surfaces of the wall portions 12 and 12^a forming the air space 12^b between them. Likewise the outer plates 10' and 11' are designed to form the outer surfaces of the wall portions.

In the practical operation of concrete wall machines of the class to which this improvement relates, the machine including the inner and outer plates is positioned along the line of operation upon or along a suitable base or foundation, the same being supported upon wheels or rollers 13 journaled in brackets 14 formed at the lower ends of substantially vertical bars 15 shown in this instance as secured against the outer faces 75 of the outer plates and constituting braces or reinforcement means for such plates. Bars 16 are connected to the inner faces of the plates 10 and 11 and constitute reinforcements for the same. The several plates are 80 maintained in parallelism by any suitable means and the plates of each pair are adapted to be fixed at definite distances apart and so maintained during the building of a certain wall construction. As shown herein, 85 the upper ends of the bars 15 are formed with heads 17 and the upper ends of the bars 16 are formed with heads 18 forming nuts and bearings respectively for shafts 19 extending fully across the machine and provided preferably with hand wheels 20 at both ends for convenience of manipulation thereof. Each of the shafts 19 is provided with right and left screw threads co-operating with the heads 17, but is smooth 90 at its middle portion where it has free slideable movement with respect to the heads 18. At 21 I show distance rods extending between the heads pertaining to the pairs of plates. In other words, the distance rods 100 21 are connected to the heads through ears 22 whereby the plates of each pair are fixed as to distance apart and are so locked as by set screws 23. This adjustment is made according to the design or size of each wall construction, and when once made, is not changed until such wall is completed. It will be understood that through the distance rods 21 the adjustment of either outer plate 95 10' or 11' will cause a like movement in the 110

same direction of its companion plate 10 or 11, and because of the lateral movement of this pair of plates in a certain direction due to the rotation of the shafts 19, the other pair of plates will be moved simultaneously to a similar distance and in the opposite direction from the first pair. The inner plate of one pair cooperates with the outer plate of the other pair to form one of the wall portions either 12 or 12^a, and likewise the other inner plate cooperates with the other outer plate to form the other wall portion.

Assuming that the machine is adjusted as shown in full lines in Fig. 3 and supported upon a suitable base or foundation represented by track members 24 of any suitable length, the spaces between the outer walls of the inner plates and the inner walls of the outer plates are filled and tamped with a soft material with any desired amount or nature of reinforcing devices, said material being of a consistency to solidify in a comparatively short time. The several plates are provided with registering holes 25 through which a plug or bar 26 is adapted to pass. Said plug is designed to be withdrawn longitudinally from the holes and from the green wall after the tamping is completed, leaving a transverse hole through the wall through which a transverse bar 27 is adapted to be passed subsequently for supporting the track members 24 for supporting the machine during the formation of the next upper course. After the machine has been filled with green material as set forth above, it is adapted to be moved lengthwise to a distance substantially equal to its length, such movement being made along the track members 24 after loosening the plates from the wall section already formed. This loosening is effected by rotation of the shafts 19 by manipulation of the hand wheels 20 at either side of the machine, such rotation causing the heads 17 to be forced bodily apart, and through the connections 21 above described the inner plates pertaining to the same pairs are caused to approach each other as indicated in dotted lines in Fig. 3. All of the plates, therefore, are free from the section of green wall, and the plug 26 having been removed, the machine is rolled easily along the track members 24 to form the next section. Rotation of the shafts 19 in the opposite direction, therefore, restores the machine so that the plates are properly spaced in accordance with the design of the wall or until the plates are caused to clamp against the wall sections previously formed. The plug 26 is then slipped in place and the machine is filled and tamped as before described. With a minimum amount of care and attention, therefore, on the part of a skilled workman and with the assistance of one or two laborers, a wall may be rapidly

and accurately built by the use of this machine. The track members 24 may be of any suitable length, preferably at least several times the length of the machine, and said track members may be moved forwardly from time to time as the operation of the machine around or along the wall progresses. After one course is completed, the bars 27 are introduced into the holes formed in the course last formed which, by the time one course is completed, will have become sufficiently solidified for the machine in the operation of the next course, and the track members 24 will then be supported upon the bars 27 in their new position. The machine is then applied to the new course and the work is continued from course to course until the wall is completed.

In the tightening of the plates in securing the machine to a previously formed course preliminary to filling and tamping, the length of the heads 17 and 18 along the shafts 19, together with the stiffness of the bars 15, may be depended upon to maintain the parallelism of the plates, but as a precaution to prevent the possibility that a careless workman may clamp the previous wall too tightly and thereby tend to cause the wall to become tapered upwardly, I may use additional means shown herein in the form of gage collars 28 shown in Fig. 3. These collars are made in standard lengths according to the thicknesses of the wall members 12 and 12^a, and when applied to the shafts between the heads, will limit the movement of such heads toward each other in an obvious manner. The collars, however, will not prevent the free outward movement for loosening of the plates.

For convenience the machine is preferably made symmetrical with respect to its several ends, and hence may be operated in either direction, but for convenience of understanding the description, the arrows on Figs. 1 and 2 may be understood as representing the direction of operation of the machine step-by-step. The ends of the inner plates 10 and 11 are notched as indicated at 29, and 30 indicates a tie bar having upturned ends 31. This tie bar may be of any suitable nature and adapted to be placed in position in the notches 29 at the rear end of the machine. The upturned ends are designed to be located at any suitable part of the interior of the wall members, and when the material is poured and tamped into position in the machine, the tie bar 30 will be anchored in place and constitute therefore a rigid bracing connection between the two portions of the wall. When the machine is moved forwardly to take a new position, the notches 29 allow the machine to move directly from the tie bar without interference with its connection with the wall just formed. One of these tie bars may be used

at each setting of the machine or at any greater intervals, as may be found desirable or necessary.

Obviously several of these machines may 5 be employed simultaneously on the same job, and while a single machine as described is satisfactory for building straight walls, for the purpose of forming corners it is preferable to use two machines in connection 10 with each other as shown in Fig. 4.

From the nature of the machine set forth herein, it is obvious that it may be adjusted so as to register with the inner corner of the wall construction irrespective of the distance of last adjustment of the machine. In 15 other words, so far as the operation of the machine is concerned, the rear end thereof may overlap any desired amount of the last formed wall section. At the ends of the 20 outer plates are formed lugs 32. Such lugs at the front end of the outer plate forming the inner surface of the wall are adapted to be secured directly to the corresponding lugs of the next machine. The lugs 32, however, at the front end of the outer plate forming 25 the outer surface of the wall are connected to auxiliary plates 33 hinged together in lugs 32' to form the outer corner of the wall, the opposite end of the forward auxiliary plate being connected to the lugs 30 of the next machine. The air space between the wall members at the corner is formed by an angular or L-shaped solid core 34 shown best in Fig. 5 and comprising 35 rabbeted vertical end edges 35 with which the inner plates of the machines coöperate when in position to form the wall bracing of desired thickness. Said core, however, may be elevated with comparative ease after 40 the machine parts are loosened as already described. The cores 34 may be of any suitable comparatively cheap construction and may be provided in standard sizes for co-operation with the adjustable machine in 45 accordance with the desired width of the air space between the wall sections. The holes formed temporarily in the wall by the plug 26 may be employed for supporting temporary scaffolding during the subsequent 50 building operations and may be plugged up finally at any desired time, either by mortar or other material. In the ordinary practice of this invention, the wall surfaces are left in proper condition for direct application 55 of plaster, stucco or the like, without the necessity for employing any kind of lathing, and because of the air space 12^b, the wall is always perfectly dry.

From the foregoing description and 60 illustrations referred to therein, it will be obvious that starting with a level foundation, the adjustable machine including the plurality of side plates may be moved forwardly step-by-step along the line of operation, as upon the foundation and then sub-

sequently upon the track members 24 supported in the manner described, without necessitating the expenditure of particular care or time in the leveling preliminary to the introduction of a new charge of wall 75 material within the machine. In other words, with a proper foundation to begin with, and with the exercise of ordinary reasonable care in the manipulation of the machine in the manner described, the machine 75 may be considered as automatically leveling. It will be noted also that the means employed for supporting the machine may be supported upon any course of the wall already built for the purpose of receiving new charges of wall material. In other words, if the uppermost course of the completed wall is found to be too soft or green on any occasion for supporting the machine in the formation of a succeeding 80 course, the bars 27 may be projected through the wall at any level below the last made course or upon that portion of the wall which is reliably set for the purpose. The only consideration in this connection is that 85 the track members employed at any particular time be of a sufficient height for the purpose of supporting the portable machine at the proper elevation.

I claim:—

1. In a concrete wall machine, the combination of a plurality of parallel side plates, a plurality of rollers journaled to said plates for supporting them, track members for supporting the rollers, means to manipulate 100 the plates toward and from each other to adjust them in operative position or to release the same from a wall section, said plates being formed with transverse aligned holes, a plug held temporarily in said holes 105 during the formation of a wall section for forming a transverse hole through the wall, and means operating through a wall hole previously thus formed for supporting said track members.

2. In a concrete wall machine, the combination of a plurality of parallel plates, means connecting the several plates transversely to maintain them in parallelism and at definite distances apart, said plates having 110 aligned holes formed transversely and horizontally therethrough, a plug extending through said holes around which the wall material is tamped and whereby a hole is formed transversely through the wall, track 115 members adjustable lengthwise of the line of operation, means extending through the previously formed transverse holes in the wall supporting said track members, and means coöperating with said plates to support the same upon the track members, substantially as set forth.

3. In a concrete machine, the combination of inner and outer spaced parallel plates arranged in pairs, adjustable distance rods 120

secured to the plates of the several pairs locking them at definite distances apart, transverse rotary shafts coöoperating with all of the plates and having right and left threaded engagement with the outer plates and having free slidable engagement with the inner plates, means to rotate the shafts from either side of the machine to cause one pair of plates to move bodily toward or from the other pair, and means to support the machine along the line of the wall upon the previously built portion thereof.

4. In a concrete wall machine, the combination of a plurality of parallel spaced plates, means to manipulate the plates toward and from each other, and means supporting the machine upon a previously constructed portion of the wall permitting step-by-step movement thereof horizontally along the line of operation, certain of said plates being provided at their rear ends with

horizontal open-ended transversely alined notches for positioning transverse wall stays, providing for the machine to withdraw from such stays while moving forwardly in a 25 horizontal direction.

5. In a concrete machine, the combination of a plurality of plates, means connecting the plates to maintain them at desired spaced distances laterally of each other, horizontal track members transportable longitudinally along the line of operation for supporting the machine in a level position while the machine is transported along the track members, and means to temporarily support the track members upon a previously built portion of the wall.
